(57) **CLAIM**

We claim the ornamental design for a spout for packaging container, as shown and described.

DESCRIPTION

FIG. 1 is a top perspective view of a spout for packaging container, showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The broken lines shown and the regions bound by the broken lines illustrate portions of the spout for packaging container that form no part of the claimed design.

1 Claim, 8 Drawing Sheets
